JOHN E. ANDERSON, OF CHICAGO, ILLINOIS, ASSIGNOR TO PLIBRICO JOINTLESS FIRE-BRICK COMPANY, OF CHICAGO, ILLINOIS, A CORPORATION OF ILLINOIS

FURNACE-WALL CONSTRUCTION

Application filed November 18, 1926. Serial No. 149,072.

This invention relates to furnace construction, and more particularly to a hollow wall construction for furnaces.

It has been recognized that greater efficiency in operation could be obtained by providing air spaces in the wall construction serving to insulate, to a certain extent, the refractory lining of the furnace chamber from the outer retaining wall so as to prevent deterioration of the outer wall and also eliminate excessive heat losses by convection and radiation. It has generally been considered, however, impossible, from a practical standpoint, to support the refractory lining of the furnace in spaced relation to the outer retaining wall of the furnace setting due to the fact that the rate of expansion and contraction of the lining is very different from the rate of expansion and contraction of the retaining wall. In order that a hollow wall construction for furnaces should be practical, it is necessary to provide means for properly supporting the refractory lining in such manner as to permit expansion and contraction thereof independently of the outer retaining wall of the setting. This has generally been considered impossible. I have found, however, that by providing suitable anchoring members it is possible to construct a hollow wall including a refractory lining or inner wall spaced away from the outer retaining wall and supported in such manner as to have independent expansion and contraction.

One of the main objects of the invention is to provide a hollow wall construction of the character stated of simple and inexpensive construction and high efficiency. A further object is to provide means for supporting the inner or lining wall of refractory material in spaced relation to the outer retaining wall in such manner as to have independent expansion and contraction while being effectively held in fixed spaced relation to the outer wall. A further object is to provide means for supporting the inner wall in such manner that the lower edge of this inner wall can be disposed in proper relation to the fire zone or the grate structure of the furnace.

Further objects will appear from the detailed description.

In the drawings:

Figure 1 is a fragmentary vertical sectional view through a furnace wall constructed in accordance with my invention; 55

Fig. 2 is a fragmentary detail perspective view partly broken away, showing the connection between one of the wall anchors and one of the inner wall or lining supporting and anchor members; 60

Fig. 3 is a perspective detail, partly broken away, of one of the outer or retaining wall anchors and the connection between the same and one of the inner wall or lining holding anchors; 65

Fig. 4 is a section taken substantially on line 4—4 of Fig. 1;

Fig. 5 is a vertical fragmentary sectional view through a conventional form of furnace showing a wall construction in accordance with my invention, as applied; and 70

Fig. 6 is a view similar to Fig. 5 of a modified form.

The outer or retaining wall 1 of the furnace setting is formed of an outer thickness or layer 2 of unvitrified brick such as is commonly used for this purpose, and an inner layer or thickness 3 of fire-brick of known type. An inner or lining wall 4 of refractory material is disposed in spaced relation to the inner face of wall 1, leaving an air space 5 between the two walls. The wall 4 is formed from refractory material which, when applied, is in a stiff plastic condition, 75 this material being applied in lumps or chunks which are beaten together by a suitable mallet to form a monolithic structure completely free of all seams or joints. This material, as stated, is in a stiff plastic condition so that the wall can be erected without a retaining form other than a suitable backing 6 which defines the outer face of the wall and provides a support against which the wall is formed, as will be obvious. As the wall 4 is of monolithic construction, it can be supported by suitable members from the outer wall 1 in such manner as to be capable of independent expansion and contraction. 80 This is an important feature of my invention, 90 95 100

as it is not possible, from a practical standpoint, to support an inner lining wall from an outer retaining wall for independent expansion and contraction and in spaced relation thereto, unless the inner wall is of monolithic construction. In a wall formed of bricks or tiles of refractory material, it is necessary to employ a suitable bonding material or mortar between the joints and this material quickly disintegrates under the influence of the high temperatures developed in the furnace with the result that openings are quickly formed through the refractory wall, thus destroying, to a large extent, its usefulness and causing, within a comparatively short time, the collapse and consequent destruction of the wall. This is particularly true where the refractory or inner lining wall is supported from the outer retaining wall in spaced relation thereto, as in applicant's construction. In fact, it has been considered impossible heretofore to so support an inner refractory or lining wall.

The wall 4 is supported by supporting and anchoring brackets 7 of substantially V-shape formed from a single strip of strap metal bent to provide an upper horizontal arm 8, a lower inclined arm 9 disposed at an acute angle to arm 8, and a short horizontal element 10 extending from the lower end of arm 9. At the apex of the bracket 7, the material is bent back upon itself to form an upwardly extending finger 11 disposed at right angles to arm 9. The arms 8 and 10 extend through suitable openings 12 provided in the backing 6, which is preferably of sheet metal.

The outer end of arm 10 is provided with a transverse slot 13 formed by slitting the metal and turning the same downwardly to form a depending flange 14, the end portion of arm 10 being turned upwardly to form an upwardly extending flange 15. Slot 13 receives the inner end arm 16A of a U-shape anchor 16 which is anchored in wall 1, as illustrated. The outer end of arm 8 is similarly secured to the outer wall. The bracket or member 7 is thus secured to the outer wall in such manner as to be capable of supporting a great weight while permitting independent expansion and contraction of the inner wall 4 due to the relative vertical and transverse movement between the arm of member 7 and the anchor members 16, slot 13 being of greater width than arm 16A, as illustrated in Figure 2. The members 7, due to their truss construction, possess great strength and for this reason are employed as hangers or supporting members for carrying the weight of the wall 4 and supporting the same from wall 1. Movement of wall 4 towards wall 1 is limited by headers 17 in the form of bricks extending from the inner layer 3 of wall 1, these headers contacting with the inner face of the sheet metal backing 6 and forming

abutment elements for the outer face of wall 4. Holding anchor members 17a of elongated U-shape are imbedded in wall 4 and extend through openings 18 in the backing 6. The member 17a is provided, adjacent its outer end, with a transverse slot 18 and flanges 19 and 20. This slot receives arm 16A of the outer wall anchor 16, member 17a being thus connected to anchor 16 in the same manner as the arms of member 7 are connected to their respective anchors. The members 7 and 17a thus cooperate to support the wall 4 from wall 1 and to hold it against movement away from the outer retaining wall, the headers 17 limiting movement of the inner refractory wall toward the outer wall thus maintaining the air space 5. The specific construction and arrangement of the two cooperating U-shaped anchor members 16 and 17 is disclosed more fully in the co-pending application of Ivan S. Pieters for flexible anchor filed July 21, 1926, Serial No. 123,825; and the particular construction of the member 7 and associated anchors 16 and the connections between the same are disclosed in detail in my co-pending application for flexible anchor filed November 1, 1926, Serial No. 145,466.

In practice, the wall 4 is of proper height to suit the particular furnace and conditions of use thereof. The position of the bottom of wall 4 will also be varied to suit the circumstances. In Figs. 5 and 6, I have illustrated a conventional form of furnace construction showing the wall 4 as extending below the grate 21. In Fig. 5, the air space 5 is open at its lower end thus permitting the relatively cool air which enters beneath the grate to flow upwardly through space 5, this air being heated to a certain extent from the refractory lining wall 4 and the passage of the air upwardly through the spaces 5 effectually preventing heating of the retaining wall 1. In the modified form illustrated in Fig. 6, the lower ends of the air spaces 5A are closed by flanges 4A formed at the lower ends of the walls 4. This provides dead air spaces between the inner and the outer walls which serve to effectually insulate the same and prevent heating to any appreciable extent of the outer retaining walls. In other types of furnaces in which grate structures are not employed, as in furnaces using oil or gas for fuel, the position of the lower ends of the lining walls and the height of these walls will be varied to suit conditions, as will be readily understood by those experienced in the art.

In erecting the wall 4, suitable strips or sheets of sheet metal are placed in position against the headers 17 which serve to effectually support the backing 6 thus formed, these headers doing away with any necessity for employing studding or other means for supporting the back 6, though studdings

may be employed when desired or necessary, these studdings being formed of wood and being burned out in the use of the furnace. After the walls 4 have been erected in the manner described, they are suitably dried and vitrified and the furnace is then in condition for use. In use of the furnace, the sheet metal backing 6 will eventually become oxidized and will disintegrate, after which the outer face of wall 4 will be in direct contact with the headers 17.

What I claim is:—

1. In a furnace construction, an outer retaining wall, an inner refractory lining wall spaced from said outer wall, anchor members secured in the inner wall, and anchor members secured in the outer wall and having tongue and slot connections with the inner wall anchor members for supporting the inner wall in spaced relation to said outer wall while permitting expansion and contraction of said inner wall in every direction in its plane independently of the outer wall.
2. In a furnace construction, a vertical retaining wall, an inner vertical lining wall disposed in spaced relation to the retaining wall, anchor members in the retaining wall, anchor members in the lining wall, means holding the lining against movement toward the retaining wall while permitting freedom of expansion and contraction of the lining, and connections between the retaining wall anchor members and the lining anchor members preventing movement of the lining away from the retaining wall while permitting expansion and contraction of the lining in every direction in its plane.
3. In a furnace construction, an outer retaining wall, an inner refractory lining wall spaced from the outer wall, anchor members embedded in the lining wall, and anchor members embedded in the outer wall and having universal connection with the lining wall anchor members, whereby the lining wall is free to expand and contract in every direction in the plane thereof independently of the outer wall.
4. In a furnace construction, an outer wall, a monolithic inner lining wall spaced from the outer wall, anchor members embedded in the outer wall, anchor members embedded in the inner wall, and tongue and slot connections between the anchor members permitting expansion and contraction of the inner wall in every direction in the plane thereof independently of the outer wall.

In witness whereof, I hereunto subscribe my name this 15th day of November, 1926.

JOHN E. ANDERSON.
